UNITED STATES PATENT OFFICE.

WILLIAM C. UDE, OF WEST HAVEN, CONNECTICUT.

TELEPHONE.

1,327,412.

Specification of Letters Patent. Patented Jan. 6, 1920.

Application filed August 1, 1917. Serial No. 183,998.

To all whom it may concern:

Be it known that I, WILLIAM C. UDE, a citizen of the United States, residing at West Haven, in the county of New Haven and State of Connecticut, have invented a new and useful Improvement in Telephones; and I do hereby declare the following, when taken in connection with the accompanying drawings and the characters of reference marked thereon, to be a full, clear, and exact description of the same, and which said drawings constitute part of this application and represent, in—

Fig. 1 a face view of a telephone instrument constructed in accordance with my invention.

Fig. 2 a transverse sectional view through the base, on an enlarged scale.

Fig. 3 a side view partly in section, of the upper end of the instrument.

Fig. 4 a reverse plan view of the base with the bottom plate removed and showing the switch mechanism in the open position, indicating diagrammatically the circuits.

Fig. 5 a similar view with the talking circuit in the closed position.

Fig. 6 a diagrammatical view illustrating a modified form of mechanism for operating the switch and armature.

This invention relates to an improvement in telephones. In the operation of telephone systems, it is desirable that means should be provided so that in case the subscriber leaves the talking circuit closed, the operator at the central station may be able to open that circuit and place the instrument in ringing position.

One object of this invention is to provide means whereby the operator at the central station, without additional apparatus or mechanism, may operate the switch at the subscriber's telephone to open the talking circuit provided that should have been left closed, and so that the operator at the central station can place the subscriber's telephone in condition for receiving a call. A further object of this invention is to so mount the transmitter that it may be readily turned so as to place the receiver at one side or the other, according to the convenience of the subscriber.

With these ends in view, my invention consists in the construction hereinafter described and particularly recited in the claims.

In illustrating my invention, I have

shown it applied to a fixture of the desk type, comprising a standard 7 and base 8, and instead of operating the switch by removing the receiver from a hook, the receiver 9 is arranged at the outer end of the arm 10 which is pivotally connected with a bracket 11 fixed to one side of the transmitter casing 12. The construction of the switch mechanism in the base will best

be understood by describing the operation. When the subscriber desires to call the central station, he presses a push-button 13 mounted in the base, which button is provided with a wedge-shaped collar 14 which engages with a switch plate 15 and moves the outer end of that plate 15 into engagement with a shoulder 16 formed on a latch-plate 17, this movement of the switch plate closing the talking circuit and showing central that the talking circuit is closed.

When central receives the signal, the operator applies energy which energizes a coil magnet 18 in the base drawing the armature 19 against the magnet, said magnet being in the talking circuit. When the subscriber finishes talking, he presses a button 20 in the base, which button is provided with a wedge-shaped collar 21, adapted to engage with the latch 17 so as to force that latch

out of engagement with the end of the switch plate 15 allowing that switch plate to snap back and open the talking circuit, leaving the instrument in the ringing position. In case the subscriber fails to press the button 20 when through talking, the talking circuit is left closed; and should the operator discover that the talking circuit is closed and the line not in use, the operator removes the plug which releases the energy in the talking circuit, and thereby releases the armature 19 which snaps outward, so to speak, and causes a finger 22 attached to the armature to strike the latch plate 17 and move it out of engagement with the switch plate 15, allowing that switch plate to move to the open position, so that the instrument is again placed in a ringing condition.

In case the subscriber's instrument is too far distant from the central station to operate on the talking energy, the operator discovering that the subscriber has finished talking, may apply the A. C. or ringing energy, which will actuate the armature 19 and cause it to trip the latch. The introduction of the magnet 18 into the talking circuit adds an impedance to that circuit to overcome which

I preferably introduce a non-inductive resistance 23 which is controlled by the contacts 24 and 25 which are brought together by an extension 26 on the armature 19 when 5 the greater part of the work of the magnet has been accomplished. This circuit-closing contact may be operated from any convenient part of the armature. It may be here noted that the armature is mounted 10 on a spring 27 the tendency of which is to move it away from the magnets. Instead of using an electromagnet, as shown in Figs. 4 and 5 of the drawings, I may use the ordinary induction coil 28 as shown in Fig. 6; 15 and instead of using two push-buttons 13 and 20, I may use a lever switch 29 to move the switch plate 15.

It will be apparent without illustration, 20 that instead of using an induction coil, I may use the ordinary impedance coil, or any type of coil forming an electromagnet to actuate an armature, which when released will open the talking circuit.

It is obvious that this release device may 25 be used in all telephones which have a switch or contact controlling the talking circuit. As shown in Fig. 1 of the drawings, the transmitter casing is mounted at the upper end of a standard and the receiver is 30 pivotally connected with one side thereof. Some subscribers use the receiver on one side, and others on the opposite side. To provide for turning the receiver from one side to the other, I provide a plate 30 extending upward from a standard set, and 35 this plate is formed with a round opening 31 to receive a boss 32 formed on the back of a transmitter casing 12, and this boss may be interlocked with the plate in any desired 40 manner. As herein shown, I employ a disk 33 which is secured to the end of a boss 32 so as to prevent the withdrawal of the transmitter, and if desired, a spring washer 34 may be introduced between the disk 33 and 45 the rear face of the plate 30 to provide for adjusting the necessary friction.

To limit the movement of the transmitter in one direction or the other, it is formed 50 with a stop-shoulder 35, its rear face being cut away to form shoulders 32 adapted to engage with a stop 36 on the plate 30, the transmitter being thus permitted to make a half revolution. Preferably and as herein 55 shown, the bracket 11 will be formed integral with the transmitter casing, the wires extending through this bracket and through the arm 10.

It will thus be seen that the operator at 60 central can restore the subscriber's telephone to the ringing position without resorting to any mechanism apart from the mechanism usually employed in operating telephone systems.

I claim:—
65 1. In a telephone, the combination with

a talking circuit, of a switch controlling the same, manual means for closing the switch, mechanical locking means for holding the switch in its closed position, a magnetized core energized by the talking circuit, and 70 an armature released by the said core and co-acting with the said mechanical locking means when the talking circuit is opened at central, to open the talking circuit at the telephone.

2. In a telephone, the combination with a talking circuit, of a switch controlling the same, manual means for closing the switch, mechanical locking means coacting directly 75 with the switch for holding the switch in its closed position, manual means for releasing the locking-means to permit the switch to open the talking circuit, and magnetic means operated by reducing the current of the talking circuit for releasing the said 80 mechanical locking means to permit the switch to open the talking circuit.

3. In a telephone, the combination with a talking circuit, of a switch controlling the same, a push-button for closing the switch, 85 mechanical locking means coacting directly with the switch to hold the same in its closed position, a push-button to release the said mechanical locking means for permitting the switch to open, and magnetic means 90 operated by reducing the current of the talking circuit for releasing the said mechanical locking means to permit the switch to open the talking circuit.

4. In a telephone, the combination with 100 the talking circuit, of a switch for controlling the same, manual means for closing the switch, mechanical locking means for holding the switch in its closed position, a magnetized core energized by the said talking circuit, and an armature released by the said core by reducing the current of the talking circuit and operating when so released to 105 operate the said mechanical locking means for releasing the switch for opening the 110 talking circuit.

5. In a telephone, the combination with a talking circuit, of a switch for controlling the same, manual means for closing the switch, mechanical locking means for holding the 115 switch in its closed position, a magnetized core energized by the said talking circuit, an armature released by the said core by reducing the current of the talking circuit, and a spring connected with the armature 120 and placed under tension by the operation thereof by the said core, whereby when the talking circuit is opened and the armature is released, the spring asserts itself to operate the armature for releasing the said mechanical locking mechanism which in turn permits the switch to open.

6. In a telephone, the combination with a talking circuit, of a switch for controlling the same, manual means for closing the switch, 125

mechanical locking means co-acting directly with the said switch for holding the same in its closed position, a magnetized core energized by the talking circuit, and an armature released by the said core by reducing the current of the talking circuit and operating when so released to operate the said mechanical locking means to release the switch for opening the talking circuit.

7. In a telephone, the combination with a talking circuit, of a switch controlling the same, manual means for closing the switch, mechanical locking means for holding the switch in its closed position, a magnetized core energized by the talking circuit, an armature released by the said core by reducing the current of the said talking circuit and operating when so released to operate the said mechanical locking means for releasing the said switch for opening the talking circuit, and means to open the switch manually.

8. In a telephone, the combination with the talking circuit, of a switch controlling the same, manual means for closing the switch, locking means for holding the switch in its closed position, a magnet energized by the talking circuit, an armature operated by the said magnet and adapted when released to operate the said locking means to release the switch, contacts brought together by the movement of the said armature, and a non-inductive resistance connected with the said contacts by the closing of which the current is shunted across the said magnet in the talking circuit.

In testimony whereof I have signed this specification in the presence of two subscribing witnesses.

WILLIAM C. UDE.
